KEY HOLDER

Morris Engel, Joseph H. Gerrish, and
Charles E. Woodruff, New York, N. Y.

Application May 7, 1952, Serial No. 286,576

11 Claims. (Cl. 70—456)

1

It is among the objects of the invention to provide a key holder that is neat, compact and light in weight, having but few parts, none of which are likely to become deranged, which will normally retain a plurality of keys in retracted position and which may readily be operated with but one hand to select one of such plurality of keys and release the latter so that the shank thereof will be objected from the holder for use, with the head of the key securely retained in position in the holder and which will securely retain such key in ejected position, yet permit retraction thereof into the casing.

According to the invention, these objects are accomplished by the arrangement and combination of elements hereinafter described and particularly recited in the claims.

In the accompanying drawings in which is shown one or more of various possible embodiments of the several features of the invention,

Fig. 1 is a perspective view of the key holder,

Fig. 2 is a longitudinal sectional view taken along line 2—2 of Fig. 1, showing the keys in retracted position,

Fig. 3 is a view similar to Fig. 2 showing a key in ejected position,

Fig. 4 is a sectional view taken along line 4—4 of Fig. 2,

Fig. 5 is a transverse sectional view taken along line 5—5 of Fig. 2, and

Fig. 6 is a side elevational view of a key.

Referring now to the drawings, the key holder desirably comprises a hollow casing 11 having a bottom and top wall 12 and 13 respectively. Each of the walls 12 and 13 has a plurality of parallel elongated grooves 14 therein substantially rectangular in cross section as shown in Fig. 5, the grooves in said walls being aligned respectively to form a plurality of tracks.

The grooves extend from near the rounded end wall 15 of the casing 11 to the mouth or outlet 16 thereof and each of the grooves in bottom wall 12 has a longitudinal arcuate groove 17 in its opposed walls to form a cage for a coil spring 18 thereby preventing displacement of the latter from such groove.

The grooves 14, six pairs of which are illustratively shown, serve as tracks for a plurality of keys 20, the heads 21 of the latter being cut to rectangular shape as shown so that they may readily slide in the associated track. By reason of the rectangular conformation of the heads 21, the shanks 22 of the keys 20 which extend at right angles to the heads, will be retained parallel to the tracks so that such shanks may be ejected outwardly from the outlet 16 of the casing by the associated coil springs 18 which are compressed between the end of the groove in the bottom wall 12 and the associated head 21.

As shown in Figs. 1, 2 and 3, the heads of the keys are retained in the casing 11 by means of an outlet plate 23 which extends across the outlet 16, being affixed at each of the side edges

2

thereof by screws 24. Plate 23 has a plurality of slots 25 therethrough, of width such as to readily permit the shank 22 of the key to pass therethrough and of length such that the edges 26 of the head which extend laterally beyond the shank 22 will abut against the adjacent edges of slots 25 as shown in Fig. 3 to retain the head of the key in the casing 11.

Means are desirably provided to retain the plurality of keys 20 in retracted position in the casing. As shown in Figs. 2, 3 and 4, such means desirably comprises a latch plate 31 of resilient material such as spring steel which is affixed by rivets 32 at its lateral protruding edges 33 to the top plate 13. The latch plate 31 desirably has a plurality of spaced parallel fingers 34, lying in substantially the same plane, flush against the top surface of wall 13 and extending rearwardly toward the end 15 of the casing. The ends 35 of fingers 34 are downwardly bent as shown in Figs. 2 and 3 and extend respectively through a plurality of transversely aligned openings 36 in top wall 13. The downwardly bent ends 35 of the fingers 34 are so positioned as to coat with the laterally protruding edges 26 of head 21 of the keys as shown in Fig. 2 so that the outward movement of the keys 20 from the casing 11 by reason of the compressed coil springs 18 will be restrained.

Means are desirably provided to select and release any one of the plurality of keys 20 retained in retracted position as above pointed out. To this end as shown in Figs. 2, 3 and 4, a selector arm 41 is pivotally mounted at its rear end 42 on the top wall 13 of the casing by means of a pivot pin 43. The top wall 13 desirably has a raised boss 44 centrally located thereon adjacent the curved end 15 of the casing 11 and said boss has a longitudinal slot 45 therethrough in which the pin 43 may both rotate and slide. The selector arm 41 is desirably retained in its rearmost position as shown in Figs. 2 and 4, with the pin 43 abutting against the end 46 of slot 45, by means of a spring 47, mounted at its midpoint by means of a rivet 48 affixed in the top wall of the casing and extending through a loop 49 in such spring. Thus, with the end 51 of the spring against the peripheral upstanding rim 52 of top wall 13, the tensed end 53 of the spring will be urged against a collar 54 encompassing pin 43 to retain the selector arm in its rearmost position.

The selector arm 41 desirably has a trip lug 56 cut out therefrom approximately in the center of the lever midway between its ends, which lug is bent downwardly as shown and in the normal rearmost position of the lever is longitudinally spaced from an upwardly inclined cam finger 57 formed integral with each of the fingers 34 of latch plate 31 near the ends 35 thereof.

The latch plate 31 desirably has a forwardly extending arm 58 integral therewith which is also

of resilient spring metal. The end 59 of arm 58 is positioned beneath the rear edge 61 of a second latch plate 62 which desirably has transversely aligned notches 63 in the lateral edges 64 thereof, through each of which extends an upstanding stud 65, the latter having a rounded base 66 affixed to the top wall 13 of the casing and on which the periphery of the notches 63 rests. The latch plate 62 also desirably has a plurality of forwardly extending parallel fingers 67 each having a downwardly bent end 68 which extends respectively through a plurality of transversely aligned openings 69 in the top wall 13 near the outlet 16 of the casing. The ends 68 of fingers 67 serve to retain the ejected keys in their outermost position by abutting against the laterally projecting edge 26 of the head 21 of the key 20 as shown in Fig. 3.

In order to retain the lever 41 and the latch plates 31 and 62 in position on the top wall 13, a cover plate 71 is provided which conforms in contour to the upstanding peripheral rim 52 of top wall 13 and is affixed thereon as by means of screws 72. Thus, the pivot pin 43 is restrained from dislodgment from the slot 45 by the adjacent undersurface of the cover plate and the pivoted latch plate 62 is retained in position by means of rounded studs 73 affixed to the undersurface of the cover plate and which abut respectively against the outer end of studs 65. The cover plate 71 desirably has an arcuate slot 75 therein positioned over the free edge 61 of pivoted latch plate 62 as clearly shown in Figs. 2 and 3. The slot 75 desirably has a plurality of notches 77 in the front edge 78 thereof which are radially aligned with the axis of rotation of lever 41 and with the upstanding cam fingers 57 of latch plate 31.

In order to move the lever 41, a stud 79 is mounted in one end of the lever 41 and extends at right angle thereto outwardly through arcuate slot 75. The stud desirably has a knob 81 affixed at its outer end and desirably conformed as a pointer which may coact with numerals associated with each of the notches 77.

To use the holder, the key 20 shown in Fig. 6 desirably has its head 21 conformed to rectangular shape so that with the outlet cover removed it may readily fit in the tracks in the casing formed by the associated pairs of grooves 14. The desired number of keys 20, illustratively six, in the embodiment herein shown, are positioned in the associated tracks and forced thereinto against the tension of the associated coil spring 18. In order that the keys may be moved past the end 68 of fingers 67, which normally restrain such inward movement, the knob 81 is pressed so that the stud 79 which normally is retained in its outermost position by reason of the coaction of resilient arm 58 against the edge 61 of latch plate 62 against which the stud 79 rests, will be moved inwardly. This will cause the latch plate 62 to pivot in a counterclockwise direction as shown in Fig. 3 about pivot studs 65 against the tension of arm 58 and the downwardly bent ends 68 of fingers 67 will be moved out of openings 69 and out of the path of movement of the heads of the keys.

The keys are thereupon moved inwardly into the associated tracks until the heads 21 thereof abut against the downwardly bent ends 35 of fingers 34. Continued inward movement of the keys will cause the ends 35 to be cammed upwardly until the heads 21 move past such ends. At such time the ends 35 will snap downwardly so

that the laterally projecting edges 26 of the heads 21 will be urged against the ends 35 by the coil springs 18 and such ends will retain the keys in retracted position. The outlet cover plate 23 may then be affixed to the outlet 16 of the casing by means of screws 24.

To eject any desired key from the casing, it is merely necessary for the user to move the pointer knob 81 along arcuate slot 75 until such pointer is aligned with a number associated with the desired key. Such movement of the lever will position the downwardly bent finger 56 thereof to the rear of the cam member 57 of the finger 34 associated with the desired key as shown in Fig. 2. The user then need merely move the button forwardly so that the stud 79 thereof will enter the notch 77 associated with the desired key. Such forward movement of the stud will cause a similar movement of the lever 41, which movement is permitted by reason of the sliding mount of pivot pin 43 in slot 45. As the lever 41 moves forward, the downwardly bent finger 56 thereof will engage cam member 57 and cause the latter to slide upwardly on finger 56 thereby lifting the downwardly bent end 35 of the associated finger 34 out of the path of the laterally projecting edge 26 of the head 21 of the selected key. Consequently, such key will be ejected by reason of the associated coil spring 18 and will move outwardly from the casing. The head 21 of such key, as it moves past end 68 of finger 67 of latch plate 62 will cam such end upwardly and the latter will be released when the edge 26 of the head 21 moves past. Thus, the head 21 of the key will be retained in the casing abutting against the outlet plate 23 and the key will be restrained from inward movement into the casing by reason of the downwardly bent end 68 of finger 67 abutting against the edge 26 thereof.

The key is then used in conventional manner to open a lock, the casing serving as the handle or head of the key to facilitate turning thereof. After the key has been used, it may readily be moved to retracted position in the casing by first pressing down on button 81 which will cause the latch plate 62 to pivot as hereinabove described to move the end 68 of finger 67 out of the path of movement of the head of the key. The key then is pushed inwardly as far as possible until it is locked in retracted position by the end 35 of finger 34 also as previously described.

With the construction above described, a relatively compact key holder is provided which occupies little more space than the plurality of keys that it accommodates. As the holder can be operated with but one hand, the fumbling of the conventional key container or key ring to select the desired key is eliminated and as the user is acquainted with the location of the keys in the casing, the holder may be operated even without any light to select a key, for example, to open a front door.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described our invention, what we claim as new and desire to secure by Letters Patent of the United States is:

1. A key holder comprising an elongated casing having a top and bottom wall and an outlet at

one end thereof, a plurality of parallel key tracks in said casing in communication with said outlet, resilient means associated with said tracks normally to urge a key in each track out of said outlet, a resilient latch plate affixed to the outer surface of said top wall and having a plurality of spaced parallel fingers aligned respectively with said tracks and extending toward the rear of said casing, each of said fingers having a downwardly bent end extending through openings in said top wall into said tracks respectively, whereby the head of a key in each track may abut against the associated downwardly bent end to be retained in retracted position, means selectively to lift any one of said fingers to move the associated downwardly bent end away from said key head for release of such key and means to limit the outward movement of such released key through said outlet.

2. The combination set forth in claim 1 in which the means to limit the outward movement of the released key comprises a plate affixed to the outlet of said casing, said plate having a plurality of slots therethrough aligned respectively with said tracks, the head of such keys abutting against the inner peripheries of said slots when the key is released to limit its outward movement from the casing.

3. The combination set forth in claim 1 in which a second latch plate is mounted on said top wall adjacent the outlet of the casing, said second latch plate having a plurality of spaced parallel fingers aligned respectively with said tracks and extending toward the outlet of said casing, each of said second latch plate fingers having a downwardly bent end extending through openings in said top wall into said tracks respectively, whereby when the head of a key is positioned between the outlet and the downwardly bent end of a second latch plate finger the latter will restrain inward movement of said key into the casing.

4. The combination set forth in claim 1 in which said plurality of parallel key tracks comprise elongated grooves in the opposed surfaces of said top and bottom walls, pairs of grooves in said top and bottom walls being transversely aligned to form tracks.

5. The combination set forth in claim 1 in which the means to lift said fingers comprises an upwardly bent cam member on each of said fingers of said latch plate adjacent the downwardly bent end thereof and directed toward the rear end of said casing, said cam members being substantially transversely aligned across the top wall of said casing, a selector arm pivoted at its rear end on said top wall adjacent the rear end of said housing and extending toward said outlet, said selector arm being mounted for longitudinal movement, a trip lug on said selector arm normally spaced from said cam members and designed to raise the latter and the associated finger when moved into engagement therewith and means to effect longitudinal movement of said selector arm to bring the trip lug thereon into engagement with any one of said cam members.

6. The combination set forth in claim 5 in which said selector arm has a pivot pin at the rear end slidably and rotatably mounted in a slot in said top wall, and resilient means associated with said pin normally to retain the selector arm in rearmost position whereby upon forward movement of said selector arm, the trip lug thereon will engage one of said cam members.

7. The combination set forth in claim 5 in

which a cover plate is positioned over said top wall and is slightly spaced therefrom, said selector arm has a pivot pin at the rear end thereof slidably and rotatably mounted in a slot in said top wall, resilient means associated with said pin normally to retain the selector arm in rearmost position, said cover plate having an arcuate slot therein adjacent the free end of said selector arm, said slot having a plurality of spaced grooves in the front edge thereof aligned respectively with said fingers, a stud connected to the free end of said selector arm extends outwardly through said slot whereby said selector arm may be pivoted to move the stud into alignment with any one of said grooves and upon forward movement of said stud into said selected groove, the trip lug thereon will engage the cam member on the associated finger to release the key in the associated track.

20 8. The combination set forth in claim 1 in which means are provided to lock the released key in outward position, said means comprising a second resilient latch plate pivotally mounted on said top wall at each of the lateral edges thereof near the outlet of said casing, said second latch plate having a plurality of spaced parallel fingers aligned respectively with said tracks and extending toward the outlet of said casing, each of the fingers of said second latch plate having a downwardly bent end extending through openings in said top wall into said tracks respectively, whereby the head of a key in each track may abut against the associated downwardly bent end of a finger of the second latch plate to be retained in outward position and means to lift all of the fingers of said second latch plate to move any one of their downwardly bent ends away from said key for release of the latter.

9. The combination set forth in claim 8 in which said first latch plate has an upwardly bent arm positioned beneath the rear edge of said second latch plate to retain the downwardly bent ends of the latter in the associated openings and the means to lift all of the fingers of said second latch plate comprises a slidably mounted stud movable against the rear edge of said second latch plate to move the latter toward the top plate against the tension of said arm whereby the second latch plate will pivot to move the downwardly bent ends thereof out of the associated openings to release the keys.

10. The combination set forth in claim 1 in which said plurality of parallel key tracks comprise elongated grooves in the opposed surfaces of said top and bottom walls, pairs of grooves in said top and bottom walls being transversely aligned to form tracks, and the resilient means associated with said tracks comprises a coil spring positioned in each groove in said bottom wall.

11. The combination set forth in claim 10 in which said grooves are rectangular in cross section and the opposed walls of said grooves in the bottom wall have longitudinal arcuate grooves therein to form a cage for the associated coil spring.
